UNITED STATES PATENT OFFICE.

JOHN W. LEETE, OF SOUTH MERIDEN, CONNECTICUT.

VEHICLE FIFTH-WHEEL.

SPECIFICATION forming part of Letters Patent No. 296,855, dated April 15, 1884.

Application filed December 4, 1883. (No model.)

To all whom it may concern:

Be it known that I, JOHN W. LEETE, a citizen of the United States of America, residing at South Meriden, in the county of New Haven and State of Connecticut, have invented certain new and useful Improvements in Axle-Couplings for Carriages, of which the following is a specification, reference being had thereto in the accompanying drawings.

10 My invention relates to improvements in axle-couplings for carriages, and has for its object the production of a coupling in which no king-bolt is used, but has a pivot formed by interlocking circular parts, as will be hereinafter more particularly set forth and claimed.

15 The accompanying drawings illustrate what I consider the best means of carrying the invention into practice.

Figure 1 is an inverted plan of the device; 20 Fig. 2, a vertical central section taken longitudinally through Fig. 1, but with the parts in the proper position; Figs. 3 and 4, details of the band or ring; Fig. 5, a detail plan view of one of the seats.

25 Similar letters of reference indicate corresponding parts wherever they occur.

A is the bar which supports the upper part of the coupling in front. B is the bar on which the lower part of the coupling is secured. 30 The upper part of the coupling forms the part circle C, the front ends of which are secured to a metal plate, D, which is secured to the bar A. The middle of the part circle C, in the rear, is provided with a clip, C', which receives the reach E. The lower part of the coupling is formed of two short arcs, C² C², united by a metal plate, F, secured to the upper side of the bar B. The clip C', on the circle C, sets out from and a little below the 35 said circle, so that a space is left between the circle and the reach E, which will allow the segments C² to project under the reach when necessary. The pivot on which the parts turn is formed as follows: At the center of 40 the plate D an annular seat, d, is formed having the exterior walls, d', and a central circular stud, d''. Into this seat a ring, G, is placed, snugly fitting the same, but with liberty to revolve. On the plate F is a seat with walls 45 and central stud similar to that just described for plate D. The face of the walls of seats and of the center studs fit together and en-

tirely surround and cover the ring G, as shown in Fig. 2. The ring or band G is of sufficient width to enter both seats d and f', and fitting 55 snugly in both prevents lateral movement of the parts. The ring G may be offset, as shown at g, and have a thick and a thinner end. The seats d and f will be of proper width to snugly receive the ring. The ring G being a separately-formed piece, and having a seat in both bottom and top parts, gives two wearing-surfaces instead of one, as is the case when it is secured to one or the other of the parts. Both the part F and the part D can move over it, 60 and it can move in either of the seats, thus giving a very free action of the parts. The construction of seats and ring, whereby there is both an inside and outside snug bearing, make a good joint and one which will wear 70 smoothly.

The parts are held against vertical separation by a binding-plate, H. This is held in place by bolts and nuts, as will be described. The reach E is secured to the bar A, as shown; 75 but is bent up close to it, and bears the screw-stud e, and back of this another screw-stud, e', while the clip C' is provided with the ordinary threaded limbs c'. To the front of the bar A an upwardly-extending arm, A', is secured, 80 which bears on its end a screw-threaded portion, b. The binding-plate H is provided with holes for the passage of these bolts e, e', c', and b, and when it is set in place nuts are screwed on these parts to hold the plate H. The top 85 of the bar B is provided with a pivot or center, B', which enters a bearing, H', in the cap-plate, and affords a center for the upper side of the bar. This pivot is preferably formed on a plate, H'', which covers the bottom as the 90 plate F covers the top of the bar B.

What I claim as new, and desire to secure by Letters Patent, is—

1. An axle-coupling formed with the annular seats d and f', whose exterior walls fit upon 95 each other, and having the center studs, as described, and a separately-formed ring, G, inserted in the seats and held inside and outside by the walls and center studs, as set forth.

2. An axle-coupling formed with the annular seats d and f', and uniting ring or band G, set in and held by the walls and center studs of the seats, said coupling being provided with a pivot, B', a binding-plate, H, having a bear-

ing, H', for the pivot B', and means, substantially as set forth, for securing the binding-plate.

3. In an axle-coupling, the combination of 5 the bars A and B, provided with seats d and f', a ring, G, a pivot, B', a cap-piece, H, provided with the bearing H' for the pivot, the reach E, provided with the screw-stud e, and the front arm, A', having the screw-threaded

end b, said screws adapted to pass through the 10 cap and receive nuts for holding the cap, as set forth.

In testimony whereof I affix my signature in presence of two witnesses.

JOHN W. LEETE.
